UNITED STATES PATENT OFFICE.

ROBERT WILLIAM REED, OF ROCHESTER, MINNESOTA.

SURGICAL APPLIANCE, BRACE, AND SOCKET FOR ARMS AND LEGS.

Application filed June 10, 1921. Serial No. 476,634.

To all whom it may concern:

Be it known that I, ROBERT WILLIAM REED, a subject of George V, King of England, residing at Rochester, county of Olmsted, State of Minnesota, have invented certain new and useful Improvements in Surgical Appliances, Braces, and Sockets for Arms and Legs, of which the following is a specification.

10 This invention relates to surgical appliances and particularly to all that class of moulded or formed devices adapted for use in case of deformity or operation such as arm or leg sockets, shoulder caps or braces 15 or jackets or braces for all purposes of corrective treatment or supplement or substitute.

In all such appliances the great difficulty 20 has been to secure strong and light structures that might be adapted to the individual case and all its peculiarities and requirements.

Strength, lightness and conformity have 25 been most difficult to attain. Various materials have been utilized with various degrees of satisfaction or success.

Celluloid has been variously used. The 30 problem has been to embody reinforcement in such structures so as to get maximum rigidity with minimum weight and perfection of fit.

Without attempting a discussion of all the 35 methods and combinations of materials which have been attempted in different hospitals and different countries, I will proceed to a discussion of my own method and its successful practice as demonstrated in a great variety of cases of corrective and supplementary surgical applications.

40 My examples are necessarily illustrative as it will be understood that no two cases can be exactly the same. As illustrative I have shown in the drawings:

Fig. I an arm piece in accordance with my 45 invention, and

Fig. II a section of such a piece on the cast.

My invention is capable of practice in so 50 many different ways and in such practice must be adapted to such a variety of cases that I will briefly describe a few characteristic applications both as illustrative and as practically instructive.

In making appliances for the body or 55 limbs a negative plaster cast is made in the

usual manner. This negative (not shown) is filled with liquid plaster Paris forming a positive P. This positive P, I build up for about one-eighth of an inch all around as at P¹ and then stretch on it a piece of stockingette S which I paint with non-combustible celluloid. This celluloid is conveniently prepared by adding acetone to clear scrap celluloid and putting in 2% calcium chloride to make it non-inflammable. Over this I apply 60 strips of gauze or crinoline which are laid so that each overlaps the one previously laid and these are painted on with the celluloid to form a shell-like strata 2.

When I have built this strata up to about 70 half the desired thickness I stretch a piece of rawhide 3 which has been rendered flexible and moist over the form, tacking it in place where necessary until thoroughly dry. After the rawhide has been dried in place 75 the tacks may be removed and the rawhide permanently glued in position. The rawhide should be covered with a piece of closely woven cotton material 4 which is glued to the surface of the rawhide. Care should be 80 taken to rub off any glue that has come through the material. After this the cotton surface may be painted with the celluloid solution and the strips of gauze or crinoline applied to build up a suitable thickness according to the size of the patient. The form 85 is then given a finishing coat of celluloid 5 and taken from the form and the first layers of stockingette removed. This surface is then smoothed up and painted with 90 the celluloid and the edges rubbed down. The form is then waterproof and may be washed. Vent holes may be bored as desired through the form and the form 95 equipped with desired fastenings.

In cases where a deformity has to be 100 covered, I proceed as in the previous case up to the point where the rawhide is stretched and covered with the cotton material. I then remove the form from the positive and build up the positive to normal size and again cover it with stockingette or gauze 1 as before. I then remove the built up plaster layer from the positive and replace the first layer of the form on the positive. To 105 this first layer I glue the second layer and then finish the two united layers as in the first case described.

In making arm sockets I preferably shape 110 a wooden form from caliper measurements

of the stump. I then split the block through the center and join again by screwing a piece of wood at top and bottom, and drill holes at each end for handles. The block should then be covered with French chalk and wrapped with grease proof paper. The stockingette may then be stretched on the block and the socket built up as in the limb appliances first described.

10 In making such articles as shoulder caps, a positive is made from the negative and built up at any tender spots or when necessary built out to give a normal appearance. The cap may then be made on this positive 15 so prepared in the manner described at first.

Sockets for amputation below the knee may be made by getting a positive cast of the stump and building and shaping as 20 near as possible to the normal leg. Stockingette and celluloid with a rawhide reinforcement is then built up as in other appliances.

The rawhide reinforcement embodied 25 as above gives great strength to the form without materially adding to the weight. When the rawhide is properly shaped and set it is very readily embodied in the stockingette and celluloid shell.

30 In making arch supports for the treatment of fallen arches and the like, a cast of the foot is first taken and the celluloid and rawhide are then applied in the manner heretofore described. After the raw- 35 hide is applied, a piece of hard felt is built into the arch support and the whole is covered with additional layers of celluloid until perfectly level, whereupon it is removed from the cast and finished in the 40 usual manner.

In the practice of my invention the forms may be variously made and the stockingette and celluloid built to various degrees of thickness according to the strength required 45 to support the patient. Those modifications necessary and incidental to the treatment of this class of work will of necessity be made without departing from the spirit of my invention if within the limits of the 50 appended claims.

What I therefore desire to secure by Letters Patent is:

1. An appliance of the class described comprising superimposed layers of stripped, 55 open mesh fabric laid in non-inflammable celluloid and having embodied therein a sheet of rawhide stretched and moulded

and covered with a close mesh fabric and united to its adjacent layers.

2. An appliance of the class described comprising a moulded body comprising superimposed layers of fabric laid in non-inflammable celluloid and having embodied therein a sheet of stretched and moulded rawhide embodied therein. 65

3. An appliance of the class described comprising a moulded body comprising superimposed layers of fabric laid in non-inflammable celluloid and having embodied therein a sheet of rawhide stretched and 70 moulded and covered with a close mesh fabric and united to its adjacent layers.

4. The method of forming appliances of the class described consisting in making a negative, in forming a positive cast from 75 the negative, in building up the positive, in forming thereon a shell composed of fabric laid in celluloid penetrating and uniting the same, in forming a moulded rawhide reinforcement on said shell prior to its 80 completion, in uniting fabric to said rawhide reinforcement and in uniting thereto successive laminations of fabric and celluloid solution and in finishing.

5. The method of forming appliances of 85 the class described consisting in making a negative, in forming a positive cast from the negative, in building up the positive, in forming thereon a shell composed of open mesh fabric laid in overlapping strips with 90 paintings of celluloid in solution penetrating and uniting the same, in forming a moulded rawhide reinforcement on said shell prior to its completion, in uniting a piece of close mesh fabric to said rawhide 95 reinforcement and in uniting thereto successive laminations of open mesh fabric and celluloid solution and in finishing.

6. The method of forming appliances of the class described consisting in making a 100 negative, in forming thereon a shell composed of fabric laid in celluloid penetrating and uniting the same, in forming a moulded rawhide reinforcement on said shell prior to its completion, in building in a said raw- 105 hide reinforcement in successive laminations of fabric and a celluloid solution.

In testimony whereof I affix my signature in presence of two witnesses.

ROBERT WILLIAM REED.
